(57) **CLAIM**

The ornamental design for a shoe, as shown and described.

DESCRIPTION

FIG. 1 is a front bottom perspective view of a shoe showing my new design;

FIG. 2 is a side view thereof;

FIG. 3 is a bottom view thereof; and,

FIG. 4 is a rear bottom perspective view thereof.

The broken line immediately adjacent to and surrounding the shaded area defines the bounds of the claimed design and form no part thereof. The broken lines depicting the remainder of the shoe form no part of the claimed design.
